UNITED STATES PATENT OFFICE.

CHARLES W. RICHARDS, OF BROOKLYN, AND JOSEPH F. KERNAN, OF NEW YORK, N. Y.

DESIGN FOR A REGISTER-FACE.

SPECIFICATION forming part of Design No. 35,931, dated June 3, 1902.

Application filed April 11, 1902. Serial No. 102,486. Term of patent 14 years.

To all whom it may concern:

Be it known that we, CHARLES W. RICHARDS, residing at 380 Quincy street, Brooklyn, in the county of Kings, and JOSEPH F. KERNAN, residing at 261 Central Park West, New York city, in the county of New York, State of New York, citizens of the United States, have invented and produced a new and original Design for a Register-Face, of which the following is a specification, reference being had to the accompanying drawing, forming part thereof.

The single figure of the drawing is a plan view of a register-face, showing our new design exactly as it is seen in use.

The essential feature of our design is the rectangular or square center made up of a series of smaller squares 1 1 and 2 2, of which the squares 1 1 are decorated with diagonal cross-bars 3 3 and the alternate squares 2 2 with the smaller squares 4, supported therein by the pieces 5, connecting the centers of the sides of the larger and smaller squares.

This design is inclosed in the harmonious margin—as here shown a margin composed of a series of rectangles 6 6, inclosing lozenges

7 7, the corner rectangles 8 8 being provided with cross-bars 9 9. At one end the design of the margin is varied, being composed of the longer rectangle 11 and two squares arranged at right angles thereto, the squares being provided with the rays 13 13 and the rectangle with the rays 14.

Our design is light, open, and graceful and particularly adapted to registers. It is of the so-called "unit" type and may be applied to registers of larger or smaller size and square or rectangular by adding or subtracting smaller squares 1 1 and 2 2.

Having described our invention, what we claim as new, and desire to secure by Letters Patent, is—

The design for a register-face, as herein shown and described.

In testimony whereof we have signed our names to this specification in the presence of two subscribing witnesses.

CHARLES W. RICHARDS.
JOSEPH F. KERNAN.
